Inventor
Otto Meyer,
By his Attorneys
Edgar V. Atchley & Co.

UNITED STATES PATENT OFFICE.

OTTO MEYER, OF NORTH BERGEN, NEW JERSEY.

EGG-TESTER.

1,127,794.

Specification of Letters Patent.

Patented Feb. 9, 1915.

Application filed July 1, 1913. Serial No. 776,745.

To all whom it may concern:

Be it known that I, OTTO MEYER, a citizen of the United States, and residing at North Bergen, in the county of Hudson and 5 State of New Jersey, have invented certain new and useful Improvements in Egg-Testers, of which the following is a specification, such as will enable those skilled in the art to which it appertains to make and 10 use the same.

This invention relates to means or devices for testing the condition of eggs, or determining whether they are fresh, good, or bad, and the object thereof is to provide 15 an improved device of this class by means of which the condition of an egg is tested or determined by the weight thereof; and with this and other objects in view the invention consists in a device of the class 20 specified constructed as hereinafter described and claimed.

It is a well known fact that a newly laid or fresh egg weighs more than at any other time, and that the weight thereof decreases 25 with its age, or with the change in the condition thereof from good to bad; and my improved egg tester is based upon the knowledge of this fact and its operation is controlled thereby.

30 The invention is fully disclosed in the following specification of which the accompanying drawing forms a part, in which the separate parts of my improvement are designated by suitable reference characters 35 in each of the views, and in which:—

Figure 1 is a plan view of an egg testing device made according to my invention;—Fig. 2 a central longitudinal section on the line 2—2 of Fig. 1;—Fig. 3 a transverse 40 section on the line 3—3 of Fig. 1;—Fig. 4 a view similar to Fig. 1 but showing only one end portion of the tester and showing an egg in position to be tested;—Fig. 5 a view similar to Fig. 4 but showing an egg 45 of smaller size than that shown in Fig. 4, and Fig. 6 a side view of the central portion of the tester and showing only a detail thereof.

In the practice of my invention, as shown 50 in the drawing, I provide a frame casing, or support a comprising a base plate or member a^2 one end portion of which, in the form of construction shown, is provided with raised side and end boards a^3 and a^4 , 55 and pivoted centrally, or approximately centrally of the base plate or member a^2 , as shown at a^5 , is a balance device b com-

prising two end portions b^2 and b^3 arranged in parallel planes or approximately so, and connected by a central vertical web portion 60 b^4 and, in practice, the parts b^2 , b^3 and b^4 are preferably composed of a single strip of material bent into the required form.

In the construction shown, the end portion b^2 of the balance device is normally 65 inclosed by the side and end boards a^3 and a^4 of the frame or support, and the opposite end portion of the frame or support may also be provided with side and end boards if desired, or the entire frame or 70 support may be made box-shaped in form, or in any other way. Arranged centrally and longitudinally of the end b^2 of the balance device is a tube c which is secured to the part b^2 by keepers c^2 , or in any other 75 way, and placed in the tube c is a spiral spring c^3 . The end part b^3 of the balance device is provided with raised side wings or keepers d which diverge outwardly, or in the direction of the central part of said 80 balance device, and at one side edge of said end portion is a projecting thumb or finger piece d^2 .

The side wings or keepers d form part of 85 an egg holder, another part of which consists of a yoke-shaped device e movable longitudinally of the part b^3 of the balance device, and resting on said part and provided with flaring sides, which operate in connection with the wings or keepers d 90 to form a receptacle e^2 in which, in practice, the egg to be tested is placed, and connected with the head portion of the yoke-shaped device e is a rod e^3 the free end of which enters the tube c and bears on the spring c^3 95 there. The pivoting of the balance device at a^5 is effected by means of raised V-shaped ears f with which the base or bottom member a^2 is provided at its opposite side edges, and the cross part b^4 or the ends thereof are 100 projected so as to rest in said V-shaped ears f .

Connected with the base plate or member a^2 forwardly of the pivot support at a^5 of the balance device is a vertical arm g the 105 top of which is provided with a horizontal plate g^2 which ranges longitudinally of the device and on which is placed a scale or scale plate g^3 provided at its inner edge with scale marks g^4 and on which are placed, corresponding with said scale marks, the words, 110 "New laid," "Strictly fresh," "Fresh," "Medium," "Poor," "Stale," and "Bad," and secured to the part b^3 of the balance de-

vice is a vertical arm h provided at the top thereof with an outwardly directed pointer h^2 which operates in connection with the scale marks g^4 . A fine spiral spring i is placed between the part b^2 of the balance device and the bottom or base plate a^2 , and the normal position of the balance device is that shown in Fig. 2, in which the end portion b^3 is raised and the end portion b^2 de-
10 pressed, and in this position the pointer h^2 of the arm h is at the scale mark designated by the word "Bad".

In Fig. 4 I have shown at j an egg placed in the egg receiving or holding chamber e^2 ,
15 and this operation forces the movable part e forwardly, or in the direction of the arrow x of Fig. 2, and compresses the spring c^3 and depresses the end portion b^3 of the balance device, and the size of the egg governs
20 the extent to which the movable part of the egg holder is forced forwardly, and no matter what the size of the egg may be, the operation of the tester will be exactly the same and the quality of the egg will be determined,
25 and in Fig. 5 I have shown an egg j^2 which is smaller than the egg j , and the condition of which is shown, by the pointer h^2 of the scale, to be the same as that of the egg j . In other words, both of these eggs are
30 determined to be fresh, or strictly fresh, according to the method of reading the scale. If the egg that is being tested is old and not in good condition, the end b^3 of the balance device will not be depressed to the extent
35 that it would be if the egg were fresh or good, and with the parts adjusted, as shown, the balance device and pointer h^2 would assume the position shown in Fig. 1, if a thoroughly bad egg were being tested, and as
40 will be seen, the position of the pointer h^2 in any case will indicate the condition of the egg on the scale or scale plate g^3 .

As is well known, the air cell in an egg is in the large end thereof, and as the age of
45 the egg increases, the air cell therein becomes larger and the center of gravity of the egg correspondingly moves in the direction of the smaller end thereof, and in order that my improved egg tester may work successfully,
50 the egg or eggs must be put in the tester with the smaller end pointing forwardly, as shown in Figs. 4 and 5. The successful operation of the device also depends upon the angle of the wings or keepers d ,
55 and the sides of the yoke-shaped device e which together form the egg receptacle, taken in connection with the weight of the plunger rod e^3 , but the angle of the parts d and of the sides of the part e , and the weight
60 of the plunger rod e^3 must all be determined in the manufacture of the device, and this can only be accomplished by testing the device in actual use, and this is a question de-

termined by the manufacturer, and when the device has been actually tested, it will 65 always work accurately, no matter what the size or condition of the egg or eggs may be. It will also be understood that the greater the divergence of the parts d and of the sides of the plate e , the greater the weight 70 of said part e^3 must be, as this feature of the construction determines the amount of the forward movement of the part e^3 :

In the use of this egg tester, it should be placed on a perfectly level support in 75 order to insure the exact operation thereof, and my invention is not limited to the details of construction herein shown and described, and changes in and modification of the various parts thereof may be made, 80 within the scope of the appended claims, without departing from the spirit of my invention or sacrificing its advantages.

Having fully described my invention what I claim as new and desire to secure 85 by Letters Patent is:—

1. An egg testing device comprising a stationary member, and a balance device pivoted therein, one end of said balance device being provided with an egg holder 90 formed of two parts one of which is movable and spring controlled, the stationary member being provided with a scale plate, and the balance device with a pointer operating in connection therewith. 95

2. An egg testing device comprising a stationary member, and a balance device pivoted therein, one end of said balance device being provided with an egg holder, formed of two parts one of which is movable and spring controlled, the stationary member being provided with a scale plate, and the balance device with a pointer operating in connection therewith, that end of the balance device opposite the egg holder being also provided with a spiral spring which is connected therewith and with the stationary member. 100 105

3. An egg testing device comprising a stationary member and a balance device pivoted in connection therewith, one end of said balance device being provided with an egg holder and the other end being connected with a stationary member by a spring, the stationary member being also provided with 110 a scale, and the balance device with a pointer operating in connection with said scale. 115

In testimony that I claim the foregoing as my invention I have signed my name in presence of the subscribing witnesses this 120 30th day of June 1913.

OTTO MEYER.
